PROCESS OF SEPARATING MINERAL OILS

Harry T. Bennett, Tulsa, Okla., assignor to Mid-
Continent Petroleum Corporation, Tulsa, Okla.,
a corporation of Delaware

Application June 23, 1933, Serial No. 677,257

6 Claims. (Cl. 196—13)

This invention relates to processes of separating mineral oils wherein selective solvents are employed to effect the desired separation. This application is a continuation in part of an application Serial No. 519,698, filed by me on March 2, 1931.

Mineral oils, including petroleum, and especially the lubricating fractions of petroleum oil, consist largely of paraffinic and naphthenic portions which may be separated from each other by commingling the oil with a suitable selective solvent, and thereafter permitting the mixture to settle into layers, or otherwise separating the selected portion from the other portion of the oil.

Various advantages may be gained in the use of such solvents to improve the quality of lubricating oil by removing the paraffinic wax, or by removing valuable paraffinic lubricating oil from naphthenic portions of the oil.

Numerous selective solvents have been suggested for work of this kind, and in my own work, I have met with an exceptional degree of success in the use of a solvent having an odor which would be objectionable in the finished products. An advantage is gained by completely eliminating this odor from the products, even though it may not impair their functions, and aside from the odor, it is desirable to entirely remove any residual portion of the solvent diffused in the products.

One of the objects of the present invention is to provide a highly efficient method of removing the solvents from the products. More specifically stated, an object is to remove the minute residual portions of solvent which are objectionable on account of their odor, or because they reduce the efficiency of the products.

A further object is to utilize selective solvents having the various properties most desirable for commercial separation of mineral oils into naphthenic and paraffinic fractions, such solvents including ethers, and the like, having an odor which should be removed from the products, as well as other solvents which become so united with the products that they cannot be completely, or conveniently, removed by the methods heretofore employed in the use of such selective solvents.

For example, in one form of the invention, I produce high viscosity index lubricating oils highly resistant to oxidation, or sludging, and having a low carbon-forming tendency, by using an ether as a selective solvent to separate the original oil into paraffinic and naphthenic

fractions. Approximately all of the solvent can be very readily distilled from these fractions, and by a special method of distillation, I have succeeded in removing practically all traces of the solvent, aside from an infinitesimal diffused portion which imparts a slight odor to the oil. This odor is perceptible to one skilled in the art, and has been found objectionable in the high grade lubricating oils produced by the use of an ethereal selective solvent.

However, in accordance with the present invention, the numerous commercial advantages of such solvents, including BB' dichlorethyl ether, can be obtained in the separation of mineral oils, and after the separated solutions have been distilled to recover approximately all of the solvent, either product can be subjected to the deodorizing operation herein disclosed, with the result of removing extremely minute particles of solvent diffused in the oil.

With the foregoing and other objects in view, the invention comprises the novel method, construction, combination and arrangements of parts hereinafter more specifically described and shown in the accompanying drawing, which illustrates one form of the invention. However, it is to be understood that the invention comprehends changes, variations and modifications which come within the scope of the claims hereunto appended.

In the preferred form of the invention BB' dichlorethyl ether is employed as the selective solvent, but other halogenated ethers may be used, and some of the advantages of the present invention may be obtained in using various other solvents including nitrobenzene, phenol, aniline, cresol, furfural, crotonic aldehyde, dichlorethylene, trichlorethylene, etc.

To aid in describing one form of the invention, I will refer to the accompanying drawing, which is a diagrammatical view of an apparatus adapted for use in carrying out the invention.

The oil to be treated passes from a receptacle 1, through a pipe 2, to a mixer 3. The selective solvent flows from a receptacle 4, through a pipe 5, to the same mixer 3.

The solvent and oil, after being agitated in the mixer 3, are discharged through a pipe 6 to a separator 7, where the paraffinic and naphthenic portions gradually separate into layers 50 in contact with each other. The paraffinic portion, with any solvent carried therein, is discharged through a pipe 8 to a still 9 provided with a vapor line 10 leading to a condenser 11 which discharges into a tank 12.

The naphthenic solution discharged from the separator 7, likewise passes through a pipe 13 leading to a still 14 provided with a condenser 15 discharging into a tank 16.

5 The solutions in the stills 9 and 14 are preferably subjected to distillation under a vacuum, and a large portion of the solvent will be freely vaporized and discharged to the condensers, without injecting steam into the stills. However, as the distillation progresses, steam or inert gas may be introduced through pipes 17 and 18, respectively, to remove approximately all of the solvent from the oil fractions.

The water and solvent discharged from the 15 condenser 11 flow into the tank 12 where they may be permitted to settle by gravity. This tank 12 is equipped with a pipe 19 for the discharge of water, and a pipe 20 through which the recovered solvent is discharged to a return 20 pipe 21 leading to the solvent receptacle 4.

The run-down tank 16 is likewise provided with a pipe 22 for the discharge of water, and a pipe 23 through which the solvent is discharged to the return pipe 21.

25 It will now be understood that the solvent is transmitted in an endless course including the solvent receptacle 4, the separating station including the separator 7, the solvent recovery stations including the stills 9 and 14, and the return pipe 21 leading back to the solvent receptacle 4.

Approximately all of the solvent is removed from the oil fractions in the stills 9 and 14, but in commercial practice a small quantity 35 of the solvent usually remains in these oil fractions after the distilling operation.

I will now describe details of a specific method whereby any objectionable residual solvent can be removed from one or both of the oil fractions, 40 with the understanding that the scope of the invention is to be determined by the claims, and not by this specific description of details.

In the manufacture of high viscosity index lubricating oils, the objection to any indication 45 of solvent in the paraffinic product would usually be greater than the objection to solvent in the naphthenic product.

Therefore, in the preferred form of the invention, the paraffinic fraction is discharged 50 from the still 9 through a pipe 24 leading to a refining station, where the presence of any objectionable solvent is eliminated from this fraction.

The naphthenic fraction is discharged from 55 the still 14 through a pipe 25 leading to a tank 26, and if desired, this fraction may be transmitted to the above mentioned refining station as suggested by a valved pipe 27 leading from the pipe 25 to the pipe 24. In other words, 60 either, or both, of these fractions may be treated to completely eliminate the presence of objectionable solvent therein.

To illustrate this feature, I have shown a refining station, or deodorizing station, including 65 a receptacle 28 adapted to communicate with the pipe 24, said receptacle being provided with a pipe 29 through which live steam, or other gaseous fluid is injected into the oil. The contents of the receptacle 28 are preferably subjected to a high temperature, for example, above 70 200° F., and also subjected to agitation while the gaseous fluid is discharged from the pipe 29. The residual solvent is thus removed from the oil and carried out through a discharge pipe 75 30 extending from the top of the receptacle 28.

This operation of removing the solvent and its odor can be conveniently performed in a contacting kettle wherein the hot oil is commingled with a suitable adsorbent or absorbent material.

For example, in the drawing I have shown an acid agitator 31 connected to the pipe 24, a pipe 32 connecting said acid agitator to the kettle 28, a discharge pipe 33 leading from said kettle to a filter press 34, and a pipe 35 connecting the filter press to a tank 36. The acid-treatment may be dispensed with by transmitting the oil through a valve-controlled by-pass 37 connecting the pipe 24 to the pipe 32.

As a very specific example, I will state that 15 the oil in the acid agitator 31 may be treated with a small quantity of 93% or 98% sulphuric acid, using about $\frac{1}{4}$ to $\frac{1}{2}$ pound of acid for each barrel of oil. This acid-treated oil is transmitted through pipe 32 to the kettle 28 where it 20 may be commingled with a finely divided absorbent, or adsorbent, material such as fuller's earth, and subjected to a temperature of approximately 260° F. to 350° F., while undergoing agitation in the kettle.

To remove the small quantity of solvent which 25 may impart an objectionable odor to the oil, live steam may be introduced through the pipe 29 for a period of about ten to thirty minutes.

The contents of the kettle 28 are eventually 30 discharged through the pipe 33 to the filter 34 which removes the adsorbent material, while the deodorized oil passes on through the pipe 35 to the tank 36.

As a specific example, I will state that, after 35 being subjected to an ordinary acid and clay treatment, a Mid-Continent lubricating oil having a gravity of 26.4 Baumé, a flash point of 405° F., a viscosity of 255 at 100° F., and a viscosity index of 75, may be mixed with BB' dichlorethyl ether in the mixer 3 at a temperature of about 80° F. to 105° F. This mixture may consist of about two parts of the ether to one part of the oil. The same temperature may be maintained in the separator 7 where the naphthenic and paraffinic fractions gradually separate from each other. The lubricating oil in the material discharged through the pipe 8 is more paraffinic than the original oil, and it has a considerably higher viscosity index than said 45 original oil. The material discharged through pipe 13 is a solution containing a lubricating oil more naphthenic than said original oil, and the viscosity index of this naphthenic lubricating oil is lower than that of the original oil.

The temperature in the vacuum stills 9 and 14 50 may be about 280° F. during the first part of the run, and it is desirable to thereafter increase this temperature to about 330° F. while introducing live steam through the pipes 17 and 18. This 55 will ordinarily remove any substantial trace of the solvent, aside from a minute diffused portion, which may impart a perceptible odor to the oil, but any objection to this odor can be eliminated by the subsequent operation whereby the diffused solvent is removed from the product.

To simplify the illustration, I have shown a single separating chamber 7, but it is to be understood that the paraffinic fraction of the oil may be subjected to successive mixing and separating operations, using additional quantities of fresh solvent; or the naphthenic solution resulting from one separating operation may be used in preliminary mixing and separating operations, so as to remove some of the 70 75

naphthenic portions from the original oil before it is subjected to the treatment with fresh solvent.

It is, of course, understood that suitable valves and pumps will be employed to efficiently control the transmission of the several fluids from one station to another, and a complete commercial system will include numerous other details not shown in the accompanying drawing. However, this drawing is merely a diagrammatical illustration of one form of the invention, and in view of the foregoing disclosure, such details will be apparent to those skilled in the art. Furthermore, the invention extends to various modifications within the scope of the terms employed in the following claims.

I claim:

1. In the art of using selective solvents to separate lubricating oil into fractions more paraffinic and less paraffinic than the original oil, the process which comprises commingling the oil with chlorinated ether, thereafter separating the selected fraction from the other fraction, distilling from the more paraffinic fraction approximately all of the chlorinated ether contained therein, and thereafter subjecting said paraffinic fraction to a deodorizing operation whereby the ether odor is removed from the paraffinic oil.
2. The process of separating lubricating oil into fractions more paraffinic and less paraffinic than the original oil, which comprises commingling the lubricating oil stock with dichloroethyl ether, separating said fractions from each other, distilling from the more paraffinic oil approximately all of the dichloroethyl ether contained therein, and thereafter subjecting said paraffinic oil to a deodorizing operation whereby the odor of dichloroethyl ether is removed.
3. The process of separating lubricating oil into fractions more paraffinic and less paraffinic than the original oil, which comprises commingling the lubricating oil stock with dichloroethyl ether, separating said fractions from each other, distilling from the more paraffinic oil approximately all of the dichloroethyl ether contained therein, and thereafter subjecting said

paraffinic oil to a deodorizing operation whereby the odor of dichloroethyl ether is removed, said deodorizing operation including the step of subjecting the odorous paraffinic oil to a high temperature and at the same time injecting a gaseous fluid into the heated material.

4. The process of separating lubricating oil into fractions more paraffinic and less paraffinic than the original oil, which comprises commingling the lubricating oil stock with dichloroethyl ether, separating said fractions from each other, removing from the more paraffinic oil approximately all of the dichloroethyl ether contained therein, thereafter agitating said paraffinic oil at a temperature above 200° F., and at the same time removing the odorous trace of ether from the treated oil by injecting a gaseous fluid into the heated material.

5. The process of separating lubricating oil into fractions more paraffinic and less paraffinic than the original oil, which comprises commingling the lubricating oil stock with dichloroethyl ether, thereafter separating said fractions from each other, distilling from the more paraffinic fraction approximately all of the dichloroethyl ether contained therein, while injecting steam into the liquid undergoing distillation, removing said paraffinic fraction from the still, treating it with sulphuric acid, commingling the treated paraffinic oil with finely divided earth at a temperature above 200° F., and at the same time removing the odorous trace of ether from the treated oil by injecting live steam into the heated mixture.

6. In the art of using selective solvents to separate lubricating oil into fractions more paraffinic and less paraffinic than the original oil, the process which comprises commingling the oil with BB' dichloroethyl ether, thereafter separating the selected fraction from the other fraction, distilling from the more paraffinic fraction approximately all of the BB' dichloroethyl ether contained therein, and thereafter subjecting said paraffinic fraction to a deodorizing operation whereby the ether odor is removed from the paraffinic oil.

HARRY T. BENNETT.
